United States Patent Office

Des. 212,188

Patented Sept. 10, 1968

212,188

TAPE CARTRIDGE

Robert Adell, Birmingham, Mich., assignor to Adell International, Inc., Detroit, Mich., a corporation of Michigan

Filed Oct. 5, 1967, Ser. No. 8,878

Term of patent 14 years

(Cl. D26—14)

FIG. 1 is a top plan view;
 FIG. 2 is an end elevational view;
 FIG. 3 is a side view taken from the left side of FIG. 2;
 FIG. 4 is an end elevational view;
 FIG. 5 is a bottom plan view;
 FIG. 6 is a side view taken from the right side of FIG. 2;
 FIG. 7 is a top perspective view; and
 FIG. 8 is a bottom perspective view.
 I claim the ornamental design for a tape cartridge, as shown.
